COMBINED DOUBLE OUTDOOR LIGHTING FIXTURE AND SUPPORT

John Kaiser, Westchester, and Donald V. Vesely, Lombard, Ill., assignors to General Signal Corporation, Rochester, N.Y., a corporation of New York

Filed Oct. 28, 1969, Ser. No. 19,770

Term of patent 14 years

Int. Cl. D26—03

U.S. Cl. D48—31

FIG. 2

FIG. 3

FIG. 1 is a perspective view of a combined double outdoor lighting fixture and support showing our new design, the opposite side being a mirror image of the side shown;

FIG. 2 is a top plan view thereof; and

FIG. 3 is a bottom plan view thereof.

The support standard is broken away in FIG. 1 to indicate indeterminate length.

We claim:

The ornamental design for a combined double outdoor lighting fixture and support, as shown and described.
